DESIGN FOR A RIBBON FABRIC

Gerald H. Simon, San Francisco, Calif.

Application August 22, 1939, Serial No. 86,824

Term of patent 7 years

To all whom it may concern:

Be it known that I, Gerald H. Simon, a citizen of the United States and a resident of the city and county of San Francisco and State of California, have invented a new, original, and ornamental Design for a Ribbon Fabric, of which the following is a specification, reference being had to the accompanying drawing, forming part thereof.

My design comprises a multiple ribbon fabric which is tucked as shown.

I claim:

The ornamental design for a ribbon fabric, as shown and described.

GERALD H. SIMON.
